UNITED STATES PATENT OFFICE.

CARL CLAUS, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA.

TRANSFER-TABLE FOR STORAGE TOTE-BOXES.

1,317,776.

Specification of Letters Patent.

Patented Oct. 7, 1919.

Application filed March 23, 1918. Serial No. 224,401.

To all whom it may concern:

Be it known that I, CARL CLAUS, a subject of the Emperor of Germany, having declared my intention of becoming a citizen of the United States, residing in Philadelphia, in the county of Philadelphia and State of Pennsylvania, have invented certain new and useful Improvements in Transfer-Tables for Storage Tote-Boxes, whereof the following is a specification, reference being had to the accompanying drawings.

The invention relates more particularly to a transfer table which is used for transferring tote boxes or the like, in which are stored heavy materials from shelving to counters, trucks and the like, or vice versa.

An object of the invention is to provide a transfer table of the above character which is provided with means whereby the table may be lifted and conveyed from one point to another, and also with means whereby the table may be secured temporarily to the shelving with the upper surface of the table in line with a shelf, so that the tote box thereon may be drawn from the shelf on to the table.

In the drawings, which show by way of illustration one embodiment of the invention, Figure I, is a perspective view, showing a series of shelves having tote boxes thereon, and my improved transfer table in place, and with one of the tote boxes withdrawn from a shelf on to the transfer table.

Fig. II, is a view, partly in section, and partly in plan, showing one way of securing the transfer table temporarily to the shelving.

Fig. III, is a view in vertical section showing the manner of attaching the transfer table to the shelving.

Fig. IV, is a view in part similar to Fig. I, but showing a modified form of means for securing the transfer table to the shelving.

Fig. V, is a view partly in plan and partly in section, showing in detail the means for connecting the transfer table to the shelving illustrated in Fig. IV.

Fig. VI, is a vertical sectional view showing further in detail this means for securing the transfer table to the shelving.

In the drawings I have shown a case 1, having a series of shelves indicated at 2, and a series of vertical partitions indicated at 3, which divide the shelves into a series of compartments in which may be placed tote

boxes indicated at 4. These tote boxes are preferably formed of metal and are adapted to store heavy metal parts, such as bolts, screws, and the like. The tote boxes are slightly smaller than the compartments, as shown in Fig. I, of the drawings, and are adapted to be slid on to the shelves into the compartments.

My invention is directed particularly to a transfer table which is adapted to receive the tote boxes and to convey the same from one point to another. Such transfer table comprises a main supporting member 5, which is provided with depending legs or members 6, 7, 8 and 9. These members are angular in cross section, and are rigidly secured to the table proper, or supporting member 5, of the transfer table. Each leg is provided with a metal bracket 10, which is riveted to the leg. This bracket is formed with a vertical member 11, a horizontal member 12, and an angular member 13. The vertical member 11, and the angular member 13, are riveted to the leg by rivets 14 and 15, respectively. The horizontal member 12, is substantially flush with the lower end of the leg. It will be noted that this bracket 10, projects outwardly from the leg. The transfer table is provided with upwardly extending arms 16, and 17, which are connected at their upper ends to a yoke 18, which is adapted to be attached to a lifting hook 19, of a suitable crane, or the like, so that the transfer table may be moved from one point to another.

At the upper side corners of the transfer table are brackets 20. Pivotedly supported by each bracket 20, is a pawl 21. Said pawl 21, has an outwardly extending arm 22, to which one end of a spring 23, is attached. The other end of this spring is attached to a fixed lug 24. The extreme forward end of the pawl 21, has a hook end 25. Said pawl also has a stop arm 26. The spring turns the pawl so as to bring the stop arm into contact with the bracket 20. Each leg is also provided with a laterally projecting bracket 27, which is adapted to engage the partition strips.

As clearly shown in Fig. I, the transfer table is placed in front of the shelving. The brackets 10, engage the upper surface of one shelf, while the hook ends of the pawls 21, engage the metal partition strips 2, which are formed T shape in cross section for this purpose. The springs hold the pawls in en-

gagement with these partitions. The transfer table, therefore, will be firmly held in place, so that the upper surface of the table will be in line with the surface of the shelf, 5 and the tote boxes may be drawn from the shelf on to the table as clearly shown in Fig. I. When the table is in place, the angle brackets 27, bear against the partition strips, and hold the lower ends of the legs from 10 moving inwardly on the shelf. After the tote box is placed on the transfer table, the pawls may be readily released by means of their handles 22, and then the transfer table carried by crane to any point desired. The 15 table may be used either end first as it has brackets 10, at both ends thereof, and also holding pawls at both ends thereof. Of course the transfer table is equally adapted for placing the tote boxes on the shelving.

20 In Figs. IV to VI, of the drawings, I have shown a slightly modified form of transfer table and also a slightly modified form of shelving. The tote boxes in the form of the invention described in Figs. I 25 and III, are slightly narrower than the compartments which contain the same. In Fig. VI, I have shown a construction wherein the tote boxes may be of substantially the same width as the compartments, as the 30 attaching means for the transfer table is connected to a means provided for the purpose on the shelving partitions. The transfer table in this embodiment of the invention is similar in construction to that above described in connection with Figs. I, and III, 35 except, as to the attaching and supporting means, the brackets 10, have been omitted. Each leg, however, is provided with the laterally projecting bracket support 27, and 40 with an attaching means at one end of each side of the table. This attaching means consists of a bracket 28, which is riveted to the table, and which has a right angle member 29, projecting therefrom, the upper end 45 of which is bent in the form of a hook as indicated at 30. Secured to the partition walls of the shelving are brackets 31. Each bracket has laterally projecting arms 32, and 33. These hooks 30, are adapted to engage these arms so as to support the table, 50 and the laterally projecting brackets 27, engaging the partition strips, support the lower ends of the legs and hold the table from swinging about the arms, so that the surface 55 of the table will be horizontal and substantially on a line with the upper surface of the shelf with which it is associated, and,

therefore, the tote boxes may be drawn from the shelf on to the table, or moved from the table on to the shelf. This transfer table is 60 also provided with lifting arms 16, and 17, whereby it may be lifted and transferred from one position to another.

It is obvious that various changes in the details of construction and the arrangement 65 of parts may be made without departing from the spirit of the invention as set forth in the appended claims.

Having thus described my invention, I claim:

1. A transfer table for storage tote boxes comprising a support for the box; means whereby said support may be lifted; depending members at one end of said support; and table carried devices whereby said transfer 75 table may be attached to and sustained by the shelving with the supporting surface of the transfer table in line with a shelf.

2. A transfer table for storage tote boxes comprising a support for the box; means 80 whereby said support may be lifted; depending members at each end of said support; said depending members having laterally projecting brackets adapted to engage the partition strips of the shelving on which the 85 tote boxes are placed; and means at the upper side ends of the transfer table for attachment to the shelving, whereby the transfer table may be sustained with the surface of the transfer table in line with the surface 90 of the shelf on which the tote box is placed.

3. A transfer table for storage tote boxes comprising a support for the box; means whereby said support may be lifted; depending legs at each corner of the support for 95 the tote box; each leg having a projecting bracket extending beyond the end of the table, and adapted to engage a shelf; and also a laterally projecting bracket adapted to engage the partition strips of the shelving, said table having at each end thereof pivoted pawls formed with hook ends adapted to engage the partition strips for sustaining the transfer table, each pawl having a projecting handle; a stop for limiting the 100 movement of the pawl and a spring for shifting the pawl.

In testimony whereof I have hereunto signed my name at Philadelphia, Pennsylvania, this twentieth day of March, 1918.

CARL CLAUS.
